CLAIM

The ornamental design for a combined bottle and cap, substantially as shown and described.

DESCRIPTION

FIG. 1 is an exploded side elevational view of a combined bottle and cap, looking from the left side, showing my new design;

FIG. 2 is a front elevational view thereof, the reverse side being the obverse of the front side;

FIG. 3 is a side elevational view thereof, looking from the right side;

FIG. 4 is a top plan view; and

FIG. 5 is a bottom plan view.
